UNITED STATES PATENT OFFICE.

ENGELHARDT W. HOLST, OF BROCKTON, MASSACHUSETTS.

NON-CHATTERING BRAKE-HANGER FOR CAR-TRUCKS.

No. 863,277.

Specification of Letters Patent.

Patented Aug. 13, 1907.

Application filed November 20, 1906. Serial No. 344,297.

To all whom it may concern:

Be it known that I, ENGELHARDT W. HOLST, a citizen of the United States, residing at Brockton, in the county of Plymouth and State of Massachusetts, have 5 invented a new and useful Non-Chattering Brake-Hanger for Car-Trucks, of which the following is a specification.

This invention relates to brake hangers for car trucks and its object is to provide hangers which are connected 10 to the brake shoe head and the supporting bracket in such a manner as to prevent the chattering noise which is often produced when brakes are applied to the wheels of cars.

A still further object is to provide means for automatically taking up wear at the points of connection 15 between the hangers and the shoe heads and brackets.

With these and other objects in view the invention consists of certain novel features of construction and combinations of parts which will be hereinafter more 20 fully described and pointed out in the claims.

In the accompanying drawings is shown the preferred form of the invention.

In said drawings: Figure 1 is a view partly in side elevation and partly in section of the hangers, supporting bracket and shoe head; Fig. 2 is a view partly in transverse section and partly in front elevation of the hangers, bracket, and shoe head; Fig. 3 is a detail view of one of the wedges; Fig. 4 is a side elevation of a modification; and Fig. 5 is a view partly in front elevation 30 and partly in section of said modification.

Referring to the figures by character of reference, 1 is a supporting bracket having a passage 2 extending therethrough, the side walls of said passage having frusto-conical recesses 3 therein either or both of which 35 may communicate with openings 4, although if desired these openings may be dispensed with. The lower end of the passage 2 is preferably enlarged as shown at 5 and the upper end is adapted to be closed by a cap 6 detachably secured at one end between ears 7 on the 40 bracket by means of a cotter pin 8 while its other end is extended under a tongue 9 projecting from the bracket 1. Oppositely extending forged hangers 10 extend into the upper end of the passage 2 and have oppositely extending frusto-conical trunnions 11 which fit within 45 the recesses 3. The adjoining faces of the hangers are preferably slightly beveled adjacent the trunnions 11 as shown at 12 and are adapted to be contacted by opposite faces of a wedge 13 insertible between the hangers through the upper end of the passage 2. This 50 wedge has a desired number of recesses 14 in its upper end each recess containing a coiled spring 15 which is adapted to be held under tension by the cap 6 when said cap is secured in position as shown in Figs. 1 and 2. A stud 16 preferably extends downward from the cap 55 into the spring so as to prevent the upper portion of the spring from becoming displaced. Obviously the spring

15 exerts a constant downward pressure upon the wedge 13 and therefore said wedge continually presses the hangers apart so as to prevent play between the trunnions 11 and their bearings. 60

The lower ends of the hangers 10 are also provided with oppositely extending frusto-conical trunnions 17 similar to the trunnions 11 and the inner or adjoining faces of the hangers converge toward their lower ends as shown at 18 in Fig. 2. These hangers are insertible 65 into a recess 19 extending into the brake shoe head 20 from the upper face thereof. The upper portion of this recess is preferably enlarged as at 21 and frusto-conical recesses 22 are formed in opposite walls of the recess and are adapted to receive the trunnions 17. A wedge 70 23 is interposed between the converging faces 18 of the hangers and has one or more recesses 24 in its upper end in each of which is seated a coiled spring 25. These springs are adapted to be compressed and held under tension by a cap 26 which is located within a recess 75 27 in the upper face of the shoe head and extends between the hangers. This cap is pivoted at one end as shown at 28 and its other end is adapted to be secured within the recess 27 by a cotter pin 29.

From the foregoing description it will be seen that the 80 hangers 10 are capable of swinging within the bracket 1 and as fast as the trunnions 11 or the recesses 3 wear the wedge 13 will be automatically pushed downward by the springs 15 and will spread the hangers apart thereby forcing the trunnions further into the recesses 85 17 and compensating for any wear which may occur. The lower wedge 23 will operate in the same manner to take up any wear occurring upon the trunnions 17 and the bearings 22. A cotter pin 30 is preferably extended transversely through the shoe head and through 90 a slot 31 in wedge 23 so as to absolutely remove any danger of the wedge becoming dislocated. In view of the fact that the trunnions are held at all times snugly within their bearings it is apparent that chattering will not occur when the brake is applied. The wedges not 95 only constitute efficient means for forcing the trunnions into their bearings to take up wear but also hold them positively against displacement.

Instead of constructing the parts in the manner shown in Figs. 1, 2 and 3 and as hereinbefore described the parts may be formed as shown in Figs. 4 and 5. By referring to these figures it will be noticed that the supporting bracket 32 has oppositely disposed frusto-conical recesses 33 in its sides and extending into these recesses are frusto-conical trunnions 34 formed 100 at the upper ends of hangers 35. A bolt 36 extends through the trunnions and the bracket 32 and has nuts 37 thereon whereby the trunnions can be drawn toward each other so as to take up any wear which may occur between the parts. A pin 38 is placed within the bolt 110 36 so as to prevent the nuts from becoming detached. With this construction the wear will not be taken up

automatically. The hangers also have integral extending trunnions 39 at their lower ends which project into frusto-conical recesses 40 in opposite sides of the shoe heads 41 and these trunnions are held seated by a bolt 42 and tightening means 43 in the same manner as are the trunnions 34.

The preferred form of the invention has been set forth in the foregoing description but I do not limit myself thereto as I am aware that modifications may be made therein without departing from the spirit or sacrificing the advantages thereof, and I therefore reserve the right to make such changes as fairly fall within the scope of the claims.

What is claimed is:

1. The combination with an element having an opening therein and oppositely extending recesses in the walls of the opening; of hangers extending into the opening, trunnions extending in opposite directions and seated within the recesses, the adjoining faces of the hangers converging adjacent the trunnions, a wedge interposed between and bearing upon the converging faces of the hangers, and means unattached to the hangers for exerting a constant longitudinal pressure upon the wedge.
2. The combination with an element having an opening therein, and oppositely-extending recesses in the walls of the opening; of hangers extending into the opening, trunnions extending in opposite directions from the hangers and seated within the recesses, a wedge interposed between and detached from the hangers, and means for exerting a constant longitudinal pressure upon the wedge.
3. The combination with an element having an opening therein and oppositely-disposed recesses in the walls of the opening; of hangers projecting into the opening, trunnions thereon and projecting into the recesses, and spreading means detached from and interposed between the hangers adjacent the trunnions.
4. The combination with an element having an opening therein and oppositely-disposed recesses in the walls of the opening; of hangers projecting into the opening, trunnions thereon extending into the recesses, a spreading device interposed between and unattached to the hangers adjacent to the trunnions, and means for exerting a constant longitudinal pressure upon the said device.

5. The combination of an element having an opening therein and oppositely-disposed recesses in the walls of the opening; of hangers projecting through the opening, trunnions thereon disposed within the recesses, a spreading device interposed between and unattached to the hangers adjacent the trunnions, and an anchoring means intersecting the spreading device to prevent removal thereof from the opening.

6. The combination with an element having an opening therein and oppositely-disposed recesses in the walls of the opening; of hangers projecting into the opening, trunnions thereon extending into the recesses, spreading means interposed between and unattached to the hangers adjacent the trunnions, means for exerting a constant longitudinal pressure upon the spreading device, and means for closing the opening within the element.

7. The combination with an element having an opening therein, and oppositely extending tapered recesses in the walls of the opening; of hangers extending into the opening, tapered trunnions extending in opposite directions from the hangers and seated within the recesses, a wedge interposed between the hangers, a removable cap extending over one end of the opening, and a spring interposed between the cap and wedge and held under tension by the cap.

8. The combination with an element having an opening therein, and oppositely extending tapered recesses in the walls of the opening; of hangers extending into the opening, tapered trunnions extending in opposite directions from the hangers and seated within the recesses, a wedge interposed between the hangers, and a retaining pin loosely engaging the wedge.

9. The combination with a shoe head having oppositely extending tapered recesses therein, and a bracket having oppositely extending tapered recesses therein; of hangers extending into the shoe head and bracket, oppositely extending tapered trunnions upon the hangers and seated within the recesses in the bracket and shoe head, and spring pressed spreading devices within the bracket and shoe head and interposed between the hangers.

In testimony that I claim the foregoing as my own, I have hereto affixed my signature in the presence of two witnesses.

ENGELHARDT W. HOLST.
